RECOVERY TANK FOR CARPET CLEANING APPARATUS

Gilbert G. Cyphert, 4320 N. 14th St.,
Phoenix, Ariz. 85014

Filed Aug. 12, 1974, Ser. No. 496,405

Term of patent 14 years

Int. Cl. D15—05

U.S. Cl. D7—170

Fig. 1

Fig. 2

Fig. 3

Fig. 4

Fig. 5

FIG. 1 is a front perspective view of a recovery tank for carpet cleaning apparatus, showing my new design;

FIG. 2 is a front perspective view thereof, shown with the cover open and shown fragmentally for ease of illustration;

FIG. 3 is a front elevational view of the device as seen in FIG. 1;

FIG. 4 is a rear elevational view thereof; and

FIG. 5 is a right side elevational view thereof, the left side being a mirror image thereof.

I claim:

The ornamental design for a recovery tank for carpet cleaning apparatus, as shown and described.
